(57) **CLAIM**

The ornamental design for a mangrove planter, as shown and described.

DESCRIPTION

FIG. 1 is a perspective view of a mangrove planter showing the new design;

FIG. 2 is a right-side elevation view thereof;

FIG. 3 is a left-side elevation view thereof;

FIG. 4 is a front elevation view thereof;

FIG. 5 is a back elevation thereof;

FIG. 6 is a top plan view thereof;

FIG. 7 is a bottom plan view thereof; and,

FIG. 8 is a second perspective view thereof.

The broken lines depicting part of a tree in FIG. 8 are for the purpose of illustrating environmental subject matter and form no part of the claimed design.

1 Claim, 8 Drawing Sheets
